UNITED STATES PATENT OFFICE

GENE J. PARK, OF NEW YORK, N. Y.

AIRSHIP PROPELLER

Application filed May 15, 1930. Serial No. 452,618.

This invention relates to air-ship propellers and particularly to propellers having a compound form of motion in which the blades rotate on the shaft to which they are attached while the said shaft swings transversely on the drive shaft of the ship, the object being a combined stabilizing and propelling force.

Further objects are, to provide simple and efficient means to produce the above described effect, and a form of mechanism which may be easily and economically constructed.

For a full understanding and comprehension of the invention, reference will be had to the following specification and claim and to the accompanying drawing, in which:

Fig. 1 shows a front view of the propeller blades with the operating mechanism mounted on an engine of conventional design.

Fig. 2 is a fragmentary enlargement of the main elements shown in Figure 1.

Fig. 3 is a vertical section through the mechanism with the propeller shaft in upright position.

Fig. 4 is an adaptation of the device in which the propeller blade is divided into two parts; one of which is positively affixed to the transverse shaft, and the other rotatable on the said shaft.

Referring now chiefly to Figures 1, 2 and 3 of the drawing; the apparatus, in its simplest form consists of an annular gear 8 which, as shown, has an internal bevel; it may however, be of other shape if desired.

This bevel gear is affixed to the engine 9, or to the fuselage frame by means of the cap screws 10. The main shaft 11 has a T branch 12 affixed at its forward extremity and secured by the cap screw 13.

A transverse shaft 14 is positioned within the T branch and positively set by the cap screw 15. Bevel pinions 16 are rotatably mounted on the transverse shaft and these have extension shanks 17 to which the propeller collars 18 are affixed by the screws 19. Stop collars 20 are affixed to the ends of the transverse shaft and retain the pinions in position. The propeller blades are seen at 21.

In action; the main shaft 11 swings the

shaft 14 in a circular motion transverse to the axis of the said main shaft. The bevel pinions, being in mesh with the annular gear, are caused to revolve and this imparts a rotating motion to the blades 21. Thus, the blades while being swung in a circle about the main shaft axis, are also rotated at right angles thereto by the said bevel pinions. This compounds the propelling and stabilizing forces and greatly improves the efficiency of the ship.

In Figure 4; a rotating blade element 24 is mounted in conjunction with a fixed blade element 25. The effect being that the conventional form of propulsion is, in part retained, but is augmented by the action of the rotatable element 24.

While the device is shown and described in its preferred form it is susceptible to other modifications thereof and is therefore not limited narrowly to the exact details as illustrated, but is claimed broadly within the spirit and scope of the appended claim.

Having thus described my invention, what I claim as new and desire to secure by Letters Patent, is as follows:

A compound propeller mechanism for airships, which mechanism comprises an annular gear affixed to the said ship concentrically to the drive shaft thereof, a cross shaft 80 affixed to the said drive shaft, blade elements rotatably mounted on the said cross shaft and pinions on the said blade elements in mesh with the said annular gear, and fixed blade elements mounted on the said cross 85 shaft adjacent to the blade elements before mentioned.

Signed at New York, in the county of New York and State of New York, this 14th day of May, A. D. 1930.
